UNITED STATES PATENT OFFICE.

JOHN O. CARREY, OF ST. LOUIS, MISSOURI, ASSIGNOR TO C & C ENGINEERING CO., INC.,
OF ST. LOUIS, MISSOURI, A CORPORATION OF MISSOURI.

CONDENSER FOR REFRIGERATING APPARATUS.

Application filed June 28, 1926. Serial No. 119,106.

This invention relates to new and useful improvements in refrigerating apparatus and to a novel method of condensing the refrigerant.

The objects of the invention are to provide an improved condenser arranged so as to effect the cooling and condensation of the compressed refrigerant in a simple and efficient manner thereby enabling me to use a more compact condenser unit which is adapted to be placed between the compressor unit and the motor used to operate said compressor.

Other objects of the invention are to provide a condenser comprising two coiled sections, one of which is of smaller diameter and arranged within the other section, said sections having their inlet and outlet connections so disposed that the path of travel of the refrigerant through said sections is simultaneous and in opposite directions to each other in order to insure rapid dissipation of heat from said sections.

Further objects of the invention are to arrange such sections in nested relation with each other with the axes of said sections disposed coaxially with the axis of the operating shaft of said compressor and motor and to provide a suitable fan on said shaft and disposed within said coils for forcing the air radially through said sections thereby insuring efficient circulation of air through all of the coils of said sections.

With these and other objects in view, my invention consists in certain novel features of construction and arrangement of parts, hereinafter more fully described and claimed, and illustrated in the accompanying drawings, in which—

Figure 1 is a side elevational view, partly in section, of my improved refrigerating apparatus.

Figure 2 is a top plan view of the same.

Figure 3 is a vertical cross section taken transversely on line 3—3 of Figure 1.

Referring by numerals to the accompanying drawings, 10 indicates a compressor unit used for compressing the refrigerant. A shaft 11 extends from said compressor and is connected by a coupling 12 to a shaft 14 of a motor or other prime mover 15. Leading from the high pressure side of the compressor is a pipe connection 16 which communicates with the horizontally disposed tubular mem-

ber or header 17 which is of comparatively large diameter and serves as an intake manifold for a pair of condenser sections 18 and 19. The inlet ends 20 and 21 thereof are connected to said header as indicated at 22 and 23 respectively. Each condenser section is formed by coiling the pipe and the diameter of the coils of section 18 is larger than the diameter of the coils of section 19 so that the latter can be arranged within the first section 18 and spaced a suitable distance therefrom. When so arranged, the coils of section 19 run in opposite direction to the coils of section 18 and the inlet terminals 20 and 21 are connected to the opposite ends of intake manifold 17 so that the refrigerant in traversing the respective sections runs in opposite directions as indicated by arrows in Figure 2. The outlet terminals or connections 24 and 25 of section 19 and 18 are connected at spaced points to a horizontally disposed tubular member or header 26 from which leads a pipe 27 which conveys the condensed refrigerant to an expansion or cooling unit 28. A pipe 29 connects the cooling unit 28 with the low pressure side of the compressor and serves to return the refrigerant back to the compressor, whereupon the cycle of operation is repeated.

The sections 18 and 19 are disposed with their axes in a horizontal plane and preferably coaxial with shaft 14. A fan 30 provided with horizontally disposed blades 31 concentrically arranged around shaft 14, is fixed to said shaft within the inner section 19 and preferably longitudinally coextensive with said sections 18 and 19. The rotation of shaft 14 actuates fan 30 and causes air to be forced radially through the coils of said sections, thereby assisting in dissipating heat radiated by said sections, and accelerating the condensation of the refrigerant. Fresh air is drawn in through the ends of the sections 18 and 19 and replaces the air driven radially through the coils of the sections and in this manner a constant circulation of air through all of the coils is provided in an efficient and simple manner.

The provision of two coiled sections arranged in nested spaced relation with each other and having their respective inlet and outlet connections arranged so that the refrigerant is caused to traverse simultaneously both of said sections in opposite directions assures uniform distribution of heat through-

out the condensing area of the unit and prevents undue heating of one end of the condensing unit.

By arranging the condensing sections one within the other, a more compact construction is provided without interfering with the circulation of air therethrough, as the coils are spaced a sufficient distance from each other to permit free passage of air. The fan blades 10 may be of the same length as the sections so that every portion of the condenser unit is air cooled by the fan.

While I have shown the preferred form of my invention it is obvious that changes in the 15 arrangements of parts of my device could be made without departing from the spirit of my invention.

I claim:

1. In a refrigerating apparatus, a condenser unit comprising two different sized sections of coiled pipe, the smaller section being arranged within the larger and in spaced relation therewith, the inlet connections of both of said sections being disposed 25 in the same horizontal plane at the opposite ends of the respective sections, and the outlet connections of both of said sections being disposed in the same horizontal plane oppositely to said inlet connections and below 30 the longitudinal plane thereof so as to cause the refrigerant to travel through said sections in opposite directions.

2. In a refrigerating apparatus, a condenser unit comprising two horizontally disposed different sized sections of coiled pipe, the smaller section being arranged within the larger and in spaced relation therewith, the inlet connections of both of said sections being disposed in the same horizontal plane 35 at the opposite ends of the respective sections, and the outlet connections being disposed below the horizontal plane of said inlet connections so as to cause the refrigerant

to travel through said sections in opposite directions, and a fan revolvably mounted within 45 the inner section coaxially therewith for forcing the air radially through the coils of said sections.

3. In a refrigerating apparatus, a condenser unit comprising two horizontally arranged coaxial sections of coiled pipe, one of said sections being of smaller diameter than the other and arranged within the latter in spaced relation therewith, an intake header common to both of said sections, and a discharge header common to both of said sections. 50

4. In a refrigerating apparatus, a condenser unit comprising two horizontally arranged coaxial sections of coiled pipe, one of said sections being of smaller diameter than the other and arranged within the latter in spaced relation therewith, an intake header common to both of said sections, a discharge header common to both of said sections, and 55 means revolvably disposed within the inner section and spaced therefrom for forcing the air radially through the coils of said sections.

5. In a refrigerating apparatus, a condenser unit comprising two horizontally disposed coaxial sections of coiled pipe, one of said sections being of smaller diameter than the other and arranged within the latter in spaced relation therewith, an intake header common to both of said sections, a discharge 70 header common to both of said sections, and a series of horizontally disposed fan blades secured to said shaft and arranged in concentric spaced relation with the coils of the inner section for drawing the air into said sections through the ends thereof and forcing the air radially through the coils of said sections. 75

In testimony whereof I hereunto affix my signature this 4th day of June, 1926.

JOHN O. CARREY.
